LEWIS D. CHRISTIE, OF TRUMBULL, CONNECTICUT, ASSIGNOR TO THE BRYANT ELECTRIC COMPANY, OF BRIDGEPORT, CONNECTICUT, A CORPORATION OF CONNECTICUT.

FUSE PLUG.

Application filed August 15, 1924. Serial No. 732,224.

To all whom it may concern:

Be it known that I, LEWIS D. CHRISTIE, a citizen of the United States of America, residing at Trumbull, in the county of Fairfield and State of Connecticut, have invented certain new and useful Improvements in Fuse Plugs, of which the following is a specification.

My invention relates to fuse plugs and the object of my invention is to simplify and improve both its construction and the method of manufacture.

In the accompanying drawings—

Fig. 1 is a vertical section through a fuse plug in which my invention is embodied in one form.

Figs. 2, 3 and 4 are similar views of the plug in the course of manufacture.

My invention relates primarily to the center contact of the plug, but I have shown a complete structure of more or less standard type comprising a thimble body 15 of insulation, with screw shell contact 16, and metal cap 17, which holds in position the disc 18 of isinglass or the like through which, and the central aperture 19 in the cap 17, the condition of the fuse strip 20 may be observed. One end of the strip 20 is carried as usual over the top of the barrier 21 into the side well 22 of the body 15 and is there secured and electrically connected to the screw shell 16, as by solder 23. A top fill 24 of cement may be added, if desired. The opposite end of the fuse strip is connected to the center contact 25 of the plug in the improved fashion which constitutes my invention.

The center contact assembly is graphically shown in Figs. 2 to 4 inclusive. As indicated in Fig. 2 the bottom of the body 15 is apertured to form a passage 26. The center contact end of the strip is passed into this aperture and is there engaged by a pellet 27 of any appropriate conducting material which is readily deformed by pressure, for example, a malleable metal such as lead, or suitable alloy. To facilitate the seating of the pellet at the inner end of passage 26, the lower interior wall 28 of the body may be coned or otherwise shaped to lead the pellet to position when freely dropped into the upper end of the chamber of the body 15. A tool 29 is introduced through the chamber of the body 15 while the latter is held on a suitable support 30,

then deforms the pellet 27 and the end of the fuse strip which overlies the inner edge 31 of the aperture 26, thus forcing the material of the pellet down into the passage 26 and embedding the end of the fuse strip 60 therein. At the same time, the inner portion of the pellet is spread to form a mushroom head which serves not only as a gas check but also as a retainer to prevent the removal of the center contact from the body. 65

The center contact 25 is provided with a pointed shank 32, after the fashion of a thumb tack, and is now driven by tool 33 upward through the passage 26. The shank penetrates the pellet, still backed by the tool 70 29, and is offset by the latter, thus riveting or clinching the contact in position and to the pellet, while at the same time establishing good electrical connection with the fuse strip 20. 75

When the center contact assembly has been thus completed, the free end of the strip may be inserted in the well 22 and soldered, or any other appropriate connection to the screw shell 16 may be effected. 80

Various modifications in detail of both structure and method will readily occur to those dealing with the problem. For example the pellet 27 may be molded on the end of the strip 20 before the latter is inserted in position. The shape of the pellet and of the strip, and of the center contact may all be varied within the limits of my claim of invention. 85

The invention provides a cheap and easy center contact construction and assembly which is good electrically and eliminates the soldered connection between the center contact and fuse strip which is now extensively used in plugs of this character. 90

I claim as my invention:

1. A fuse plug comprising a center contact provided with a pointed shank, a fuse strip, and a soft metal engaging one end of the fuse strip and penetrated by the shank 100 of the center contact.

2. A fuse plug comprising a fuse strip, soft metal engaging one end of the fuse strip, and a center contact having a pointed shank which penetrates and is off-set in said metal to rivet said parts together in good electrical connection. 105

3. A fuse plug comprising an insulating body pierced by a passage at its entering end, a fuse strip, a body of soft metal en- 110

gaging the end of said fuse strip, together with a center contact having a pointed shank entering said passage and penetrating said soft metal and serving to hold said center contact in position in good electrical connection with the fuse strip.

4. The method of manufacturing fuse plugs which comprises engaging the end of a fuse strip with a pellet of soft metal within the chamber of the fuse plug body and forcing the shank of a center contact through an aperture in the plug body and into said soft metal to secure the contact in position on the body in good electrical connection with the fuse strip.

5. The method of manufacturing fuse plugs which comprises engaging the end of a fuse strip with a pellet of soft metal within the chamber of a fuse plug body, and forcing the shank of the center contact through an aperture in the plug body into offset connection with said soft metal to secure the contact in position in good electrical connection with the fuse strip.

6. The method of manufacturing fuse plugs which comprises the step of deforming the shank of the center contact in a body of soft metal electrically connected to an end of the fuse strip.

7. A fuse plug comprising a center contact provided with a shank, a fuse strip, and a mushroomed body of soft metal engaging the fuse strip and penetrated by the shank of the center contact.

8. A fuse plug comprising a one-piece insulating body apertured at its entering end, a screw shell side contact secured to said body, a fuse strip electrically connected to said screw shell and engaged at said aperture by soft metal, together with a center contact pin penetrating and deformed in said soft metal to establish electrical connection with the fuse strip and to maintain the center contact in position.

In testimony whereof I have signed my name to this specification.

LEWIS D. CHRISTIE.
